UNITED STATES PATENT OFFICE.

PORTE McKEEN BRADLEY, OF JOPLIN, MISSOURI.

OPEN-FRONT GAS-HEATER.

1,121,462.

Specification of Letters Patent. Patented Dec. 15, 1914.

Application filed October 5, 1912. Serial No. 724,061.

To all whom it may concern:

Be it known that I, PORTE M. BRADLEY, a citizen of the United States, and a resident of Joplin, in the county of Jasper and State 5 of Missouri, have invented an Improvement in Open-Front Gas-Heaters, of which the following is a specification.

My invention is an improvement in that class of gas heaters having an open front 10 and provided with curved reflector plates extending backward and upward from the base and forming the back of the cavity or open front of the heater.

My invention is embodied in several features of construction, arrangement, and combination of parts which reduce the cost 15 and increase the strength, durability, and efficiency of the heater as compared with those of the usual type.

20 In the accompanying drawings Figure 1 is a front view of the heater. Fig. 2 is an enlarged vertical cross section of the same. Fig. 3 is a detail section on the line 3—3 of Fig. 2. Fig. 4 is a perspective view of the 25 front baffle plate. Fig. 5 is a perspective view of the rear baffle plate. Fig. 6 is a vertical section of the heater taken through its longer diameter. Fig. 7 is a horizontal section of the heater taken on the line 7—7 30 of Fig. 2. Fig. 8 is a perspective view illustrating certain details of construction and arrangement.

The body 1 of the heater is oblong in horizontal section, as shown in Fig. 7, and in the 35 process of manufacture it is stamped out of a single piece of sheet metal whose vertical edges are united at the middle of the back of the heater by a folding seam 2, as indicated in Fig. 7. The body is open at the bottom to admit air, as indicated by arrows 40 in Fig. 2, and is closed at the top, as indicated in Figs. 2 and 6. The one-piece body 1 is further constructed with integral sides 45 or wings 3 which are bent inward into parallel position and form the sides of the open front of the heater. The details of curvature of this portion of the heater are indicated in the section shown in Fig. 3. The rear curved edges of the wings 3 are bent 50 toward each other at a right angle, thus forming a flange 4, upon which the curved copper reflector 5 ordinarily employed in this class of heaters rests and is supported. In order to hold these two parts duly engaged, I solder metal lugs or tongues 6 to 55 the sides 3 and bend them outward over the

adjacent edges of the reflector 5—see especially Fig. 8. By this construction of the wings 3 integrally with the main portion of the body 1, instead of attaching them thereto as separate pieces by means of rivets or bolts, I not only lessen the cost of the heater as a whole, but increase its strength and improve its ornamental appearance.

The front baffle plate 7, shown detached 60 in Fig. 4 and arranged in due working position in Figs. 2 and 7, has a pendent flange 8 formed on its front and side edges, and it is secured to the front wall of the heater by rivets or bolts as shown. The inner end of 65 this baffle plate is curved upward and backward as shown.

The rear baffle plate 10, shown detached 70 in Fig. 5 and in working position in Fig. 2, is secured at one point only to the body of 75 the stove by means of bolts, rivets, or screws 11. In other styles of heaters of this class, the reflectors or baffle plates are ordinarily bolted to the ends as well as the front of the body, and I have therefore considerably reduced the cost of these attachments by securing them at a single point. Also by providing them with side flanges, 10^a, they are 80 stiffened to the required degree. The upper end of the baffle plate 10 is curved toward 85 the front of the heater and the inner end of baffle plate 7 is curved upward and backward, whereby the current of heated gases is directed upward and toward the front as 90 they pass between the opposed ends of the two baffles.

By the arrangement of the baffle plates, a large volume of air is introduced from the bottom of the stove so as to mix with the gas discharged from the pipe 12, arranged, 95 as shown in Fig. 2, above the reflector 5 and near the front of the heater. I thus secure a perfect combustion without the deposit of soot, which is a common incident in the use of heaters of this type. By providing a 100 space at the ends of the baffle plates between them and the ends of the body of the heater, the cool air coming in from the bottom of the stove is subjected to the action of heat rays in a way which is not practicable by 105 the old construction and arrangement and a greater calorific effect is thereby produced.

It will be noted—see Figs. 1 and 2—that 110 openings 13 are provided in the heater front just above the horizontal gas-pipe 12 which allows air to pass freely between the burner and the front baffle plate and prevents the

flame from striking directly upon the baffle plate and depositing soot thereon. Other perforations 14 are formed at the top of the heater, as indicated in Figs. 1, 2, and 6, in order to insure due admission of air to effectively support combustion and secure the highest calorific effect without the deposit of soot.

What I claim is:

- 10 A heater comprising a body having a front opening and inwardly projecting parallel wings forming the sides of said open-

ing, the rear or inner edges of the wings being bent and projecting toward each other, a back plate constituting a reflector whose side edges rest upon the in-bent portions of said wings, and right angular lugs spanning exteriorly the joint formed by said wings and reflector and secured in place, as described.

PORTE McKEEN BRADLEY.
